[57] CLAIM

The ornamental design for a supporting base for an electric fan, as shown and described.

DESCRIPTION

FIG. 1 is a front perspective view of a supporting base for an electric fan showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof, the right side being a mirror image of that shown; and,

FIG. 7 is a right and top perspective view thereof, on a reduced scale shown in use.

The broken line showing of a fan, in FIG. 7, is for illustrative purposes only and forms no part of the claimed design.

FIG. 1

FIG. 2

FIG. 3

FIG. 4

FIG. 5

FIG. 6

FIG. 7
